UNITED STATES PATENT OFFICE.

WILLIAM M. GOLDSMITH, OF CINCINNATI, OHIO.

SHORE FOR CONSTRUCTION WORK.

Application filed October 8, 1920. Serial No. 415,659.

To all whom it may concern:

Be it known that I, WILLIAM M. GOLDSMITH, a citizen of the United States of America, and a resident of Cincinnati, in the county of Hamilton and State of Ohio, have invented a new and useful Improvement in Shores for Construction Work, of which the following is a specification.

An object of my invention is to provide a shore to be used to support molds for plastic work, that can be readily expanded and contracted.

Another object is a shore that is free from projections that will obstruct workmen.

Another object is to provide a shore that will not become accidentally released.

Another object is to provide a device of the type referred to that will maintain an adjusted position.

Another object is to provide a shore that may operate regardless of its position.

These and other objects are attained by the means described herein and disclosed in the accompanying drawing in which:—

Fig. 1 is an elevation showing a device embodying my invention mounted in an operative position.

Fig. 2 is an enlarged sectional view on line 2—2 of Fig. 1.

Fig. 3 is an enlarged sectional view on line 3—3 of Fig. 2.

Fig. 4 is a plan view of a collar forming a detail of my invention.

Fig. 5 is a side elevation of a device shown in Fig. 4.

Fig. 6 is a plan view of the bottom plate of Fig. 3.

My invention comprises a housing A that is mounted between the two supports B and B', and thru which an adjustable standard C passes. The device is adapted to permit ready movement of the adjustable standard in a given direction and to resist movement of such standard in the opposite direction.

The housing A is preferably of square or rectangular cross section and has extending therefrom a series of perforated lugs a thru which bolts may be passed in order to mount the housing upon the supports B and B'.

The supports B and B' are preferably mounted upon the housing A diametrically opposite to one another. A central bore a' extends thru the housing A parallel with the supports B and B'. The adjustable standard C is adapted to extend thru the central bore a' and is of a diameter substan-

tially equal to that of the bore. A series of pockets a¹² are formed in the housing. These pockets taper gradually toward the top a³ of the housing. Upon the bottom of base a² of the housing is mounted a perforated plate a⁴ that is adapted to be mounted upon such base by means of bolts or screws that pass thru the countersunk perforations a⁵ and engage in the housing. Mounted upon the plate a⁴ is a perforated collar a⁶ having a series of notches a⁷ in its upper surface, which surface engages the under surface of the plate a⁴. Thru the perforations a⁸ in the collar a⁶ and thru the perforations a⁹ in the plate a⁴, extend a series of plungers a¹⁰. The plungers have heads a¹¹ at their upper ends which extend into the pockets a¹² formed in the corners of the upper or top section of the housing and communicating with the central bore. These pockets taper gradually upward from the mid-section of the housing to the upper end of the housing. Adjustable nuts a¹³ mounted upon the lower ends of the plungers, limit the extent to which said plungers and the heads thereon extend into the pockets a¹². A spring a¹⁴ is mounted on the plunger between the head thereon and the plate a². A ball a¹⁵ is disposed within each pocket, such balls being retained in the pockets by means of the plungers. The balls are sufficiently large to engage the walls of the pockets, the adjustable standard C and the head a¹¹ on the plunger. Altho I have shown a series of tapered pockets, the bore itself may be tapered and the balls held in position in the tapered bore by any desired means, such as a ring supported by the plungers. The shape of the bore and the adjustable standard can also be modified if desired.

The operation of my device is as follows:—

The adjustable standard C extends thru the bore of the casing A, the plate a² and the collar a⁶. The balls in the pockets a¹² are normally held in engagement with the walls of the pockets and the standard C by means of the plungers a¹⁰ actuated by the springs a¹⁴. The balls prevent the housing A together with the supports B and B' upon which the housing is fixedly mounted, from moving downward upon the standard because the balls would be forced up into the pockets. This is normally impossible because the pockets taper upward, and therefore any such relative movement of the

standard C, housing A and supports B and B' is impossible. The plungers a^{10} together with the springs thereon serve to hold the balls in such position that they will resist 5 such relative movement. When it is desired to raise the housing A and supports B and B' upon the standard C, the balls are pushed downward by the relatively opposite movement of the standard and housing 10 tending to move the balls into a larger section of the pockets and moving the balls against the yielding resistance of the spring operated plungers. When the desired adjustment has been made of the standard 15 C the balls again assume positions bearing upon the casing and the standard C. When it is desired to release the standard C from its adjusted position, a series of nails, or pointed tools of any kind or type are forced 20 between the plate a^4 and the collar a^6 . The notches a^7 make this a very simple operation. When the collar is raised from the plate a^4 the plungers a^{10} are moved away 25 from the rotors or balls a^{15} , releasing the rotors or balls and thereby making it possible to lower the housing and supports upon the standard C. When the nails or the tools are removed, the plungers again 30 assume their normal position and hold the balls upon the standard C and the casing A. Altho I have shown the adjustable standard C being round in cross section it is readily apparent that this member may be made of any form, and appropriate struc- 35 tural changes made in the casing A to accommodate such other form of adjustable standard. Either the standard C or the supports B and B' may be used as a base, the device operating equally efficient re- 40 gardless of whether the device is used as shown in Fig. 1 or if used in an inverted position from that shown. Any of the races or any other suitable expedient com- 45 monly used to retain balls within a restricted area can be employed to prevent the balls escaping from the housing if the standard is to be frequently removed from the bore in the housing. Any other means or type of rotors that will function as do the 50 balls, plungers, the plate and collar upon the housing may be resorted to without deviating from the spirit and scope of my disclosures.

What I claim is:—

55 1. In a shore the combination of a hous-

ing adapted to be mounted upon supports and having a tapering bore, a perforated plate mounted upon the housing, a perforated collar mounted upon the plate, the collar and plate having perforations in alignment with the bore of the housing, a standard extending thru the bore and perforations of the housing, plate and collar and movable therethru, a series of rotors contained within the housing and interposed between the standard and the housing, plungers extending from the collar into the bore and normally retaining the rotors in joint contact upon the housing and the standard, and yieldable means adapted to maintain the plungers in their normal positions.

2. In a shore the combination of a housing adapted to be mounted upon supports and having a tapering bore, a perforated plate mounted fixedly upon the housing, a perforated collar mounted upon the plate, the collar and the plate having perforations in alignment with the bore of the housing, a standard extending thru the bore and the perforations in the housing, plate and collar and movable therethru, a series of rotors contained within the housing and interposed between the standard and the housing, plungers extending adjustably thru perforations in the collar and the plate and normally engaging the balls, and springs mounted upon the plungers and abutting the plate.

3. In a shore the combination of a housing adapted to be mounted upon supports and having a tapered bore, a perforated plate mounted on the housing, a perforated collar mounted on the plate, the plate and collar having perforations in alignment with the bore in the housing, the collar having a series of notches upon its one surface, such surface normally engaging the plate, a standard extending thru the bore in the housing and thru the perforations in the plate and collar, and movable therethru, a series of rotors encased within the housing and interposed between the standard and the housing, and plungers mounted on the collar, extending thru the plate and abutting the rotors.

In testimony whereof, I have hereunto subscribed my name this 7th day of October, 1920.

WILLIAM M. GOLDSMITH.
